UNITED STATES PATENT OFFICE.

JAMES G. ZIMMERMAN, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

CIRCUIT-PROTECTING APPARATUS.

1,223,549.

Specification of Letters Patent. Patented Apr. 24, 1917.

Application filed May 17, 1912. Serial No. 697,892.

To all whom it may concern:

Be it known that I, JAMES G. ZIMMERMAN, a citizen of the United States, residing at Milwaukee, in the county of Milwaukee and State of Wisconsin, have invented certain new and useful Improvements in Circuit-Protecting Apparatus, of which the following is a full, clear, and exact specification.

10 This invention relates to circuit protecting apparatus.

It is a known fact that if a current is caused to flow through a conducting liquid, such as mercury, for example, there is a 15 tendency for the liquid to decrease in cross section, thereby causing the current density and resistance of the liquid to increase. This decrease in cross sectional area of such conducting liquid varies in the same sense as 20 the strength of the current passing through the conducting liquid. This means that the greater the value of current passing through the liquid, the greater will be the tendency of the liquid to decrease in cross sectional

25 area. The cross sectional area of the conducting liquid does not decrease the same amount along its whole length, however. The greatest decrease in cross sectional area occurs at the so-called weakest part of the 30 liquid. This decrease in cross sectional area of the conducting liquid at its weakest part or section caused by the passage of current is known as the "pinch effect". When the current has reached a predetermined value 35 the "pinch effect" may be so great as to reduce the cross sectional area at the weakest point to nothing, thereby breaking the electric circuit of which the conducting fluid forms a part. With an increase in the

40 "pinch effect" there is an increase in density and resistance and a corresponding increase in the potential difference between points on opposite sides of the section of the circuit at which the "pinch effect" takes place. In 45 view of the fact that the "pinch effect" increases with increase of current flow and that time is required after a flow of such current to establish the "pinch effect", a time element is introduced. I have taken ad-

50 vantage of these facts and have so connected current conducting liquid with respect to a safety operative device that the motor or other device to be protected will be cut off from its source of supply upon the occurrence of abnormal circuit conditions.

The object of my invention is therefore to provide circuit controlling and protective means adapted to meet the requirements of successful commercial operation.

The invention is illustrated in the accompanying sheet of drawings, in which Figure 1 is a diagrammatic view of a system including a motor, a circuit-breaker therefor, and means including a fluid current conducting body which is responsive in a manner to current passing therethrough to cause an operation of said circuit-breaker upon the occurrence of abnormal circuit conditions;

Figs. 2 and 3 are front and end longitudinal sectional views respectively of a receptacle containing a liquid current conducting body illustrating the so-called "pinch effect" caused by a passage of current through said liquid;

Fig. 4 is a longitudinal sectional view of 75 a vertically arranged receptacle containing a liquid capable of producing the "pinch effect"; and,

Fig. 5 illustrates the same receptacle as shown in Fig. 4 containing the liquid with 80 the current passing therethrough, showing the "pinch effect".

The various novel features of my invention will be apparent from the description and drawings, and will be particularly set 85 forth in the appended claims.

There are a great many different types of apparatus for controlling and protecting electrical circuits. These various types may be connected in systems of different description. A particular type of circuit protecting

90 means which I have found to be effective is one in which I make use of the so-called "pinch effect". For the sake of illustration, I am showing this circuit protecting 95 means as connected in the secondary circuit of an induction motor, the "pinch effect" means being adapted to cause the actuation of a device or devices for cutting off the induction motor from its source of supply. 100 This induction motor 10 is connected to a supply circuit 11 by leads 12 through a circuit-breaker 13, which is normally held in closed position by a spring 14, but which is adapted to be opened to disconnect the induction motor 10 from its source of supply by the action of current in the solenoid 15 in response to circuit conditions. The solenoid 15 is connected in a normally open circuit with a current transformer 16 which re- 105 110

ceives current directly from the main line 11. This circuit is adapted to be closed by the armature member 17 of a magnet 18 having a coil 19 connected in the secondary circuit 20 of the induction motor 10. This secondary circuit includes a variable resistance 21 and a current conducting liquid, preferably mercury 22, in a receptacle 23 having terminal members 24 and 25 passing through 5 said receptacle 23 and extending into said liquid. This liquid current conducting body 22 is connected in one phase of the secondary circuit of the induction motor and is connected in parallel with the coil 19 of the magnet 18. Also connected in branch relationship with respect to said liquid current conducting body and coil 19 of magnet 18 is a resistance 26 which may or may not be included in the circuit.

10 With the circuit-breaker 13 in closed position current flows into the primary circuit of the induction motor 10, and a current is induced to flow in the secondary circuit 20 of such induction motor, causing current not only to flow through the adjustable resistance 21 but also through the liquid conducting body 22, resistance 26, and the coil 19 of magnet 18. The current passing through the liquid current conducting body 22 causes 15 said liquid to be agitated in a manner whereby the cross sectional area of the liquid at some point is caused to decrease. With a decrease in the cross sectional area of said liquid, there is an increase in the density and 20 a corresponding increase in resistance and drop of voltage across that section of the liquid conducting body. With an increase of current there is a greater decrease in the cross sectional area at a certain place of the 25 liquid conducting body, the place at which this decrease in cross sectional area occurs being the so-called weakest point of the liquid. When the current has risen to a certain predetermined value the cross sectional 30 area at the weakest point of the liquid conducting body may be decreased to nothing. In other words, the circuit may be broken at that point. This decrease in the cross sectional area of the liquid conducting body 35 due to the passage of the current therethrough is known as the "pinch effect." The greater the "pinch effect" the greater will be the density, resistance, and corresponding drop in voltage across said liquid conducting 40 body. The coil 19 of the magnet being in parallel with the liquid conducting body 22 has the same voltage across its terminals. Current passing through the coil under normal operating conditions would not be sufficiently strong to attract the armature 17 to 45 overcome the action of spring 27 to complete at contacts 28 the circuit containing the current transformer 16 and coil 15. But when the voltage across terminals of the liquid 50 conducting body 22 has increased a predeter-

mined amount, due to the "pinch effect" caused by the current passing through said liquid, the coil 19 will be energized to the extent that the armature 17 will be attracted into closed position whereby the coil 15 will be energized by current from the current transformer 16 overcoming the action of spring 14, causing the circuit-breaker 13 to open and cutting off induction motor 10 from its source of supply. The resistance 55 26, which is connected in parallel with the liquid conducting body 22 and coil 19, is for the purpose of preventing any sparking in the liquid current conducting body in case the "pinch effect" becomes so great as to cause the liquid 22 to divide into two parts. It is not necessary that the liquid divide in two parts to cause an actuation of the magnet 18 to open the circuit-breaker 13, for the magnet 18 may be adjusted to respond to 60 any current of any particular value.

Instead of using the particular liquid receptacles shown in Figs. 1, 2, and 3, the one disclosed in Figs. 4 and 5 can be used. This one is a vertically arranged receptacle containing current conducting liquid which is capable of producing the "pinch effect" caused by the passing of current through said liquid. This vertically arranged receptacle 29 is provided with a member 30 having holes 31 to permit the passage of liquid which is caused to flow upwardly due to the "pinch effect." The restricted openings or holes 31 assist in producing the desired degree of retardation. Passing through this member 30 is one terminal 32, the other terminal 33, being shown as passing through the bottom of the receptacle 29. Receptacles of various shapes and arrangements may be used as long as the liquid within said receptacles is capable of producing the so-called "pinch effect" in response to current passing through said liquid. It is not necessary that mercury be used, for other conducting liquids are also capable of producing the "pinch effect." Neither do I limit myself to the use of liquids, for there may be various elements included in the term "fluids" which are capable of producing a "pinch effect." The fluid current conducting medium may be connected in any circuit in which current flows.

There may also be various modifications and arrangements other than that here particularly shown and described, and it is my intention to cover all such modifications and arrangements which do not involve a departure from the spirit and scope of my invention as set forth in the appended claims.

What I claim as new is:

1. In combination, an electrical circuit, and controlling means for said circuit comprising an electro-magnetically actuated element and means comprising a liquid conductor in circuit with the actuating wind-

- ing of said element for controlling the actuation of said element, said element being actuated on the passage of current of a certain value through said liquid conductor.
- 5 2. In combination, a circuit including a liquid the cross sectional area of which varies in response to abnormal circuit conditions, another circuit in which the current varies in response to changes in said liquid,
- 10 and a circuit controlling device in said last mentioned circuit responsive to said current variation.
3. In combination, a circuit including a liquid the cross sectional area of which varies in response to abnormal circuit conditions, a branch circuit in which the current varies in response to changes in said liquid, and a circuit controlling device in said last mentioned circuit responsive to said
- 20 current variation.
4. In combination, an electrical circuit, electro-magnetically actuated means for controlling said circuit, and means connected in parallel with the actuating winding of said
- 25 controlling means for producing a "pinch effect" in response to a characteristic of the current in the circuit to be controlled to cause operation of said controlling means.
5. In combination, an electrically operated
- 30 member, and a circuit including a liquid conductor connected in parallel with the operating circuit of said electrically operated member, means for supplying current to said
- 35 circuits, said liquid conductor being adapted to be agitated by current variation there-
- in to cause the actuation of said electrically operated member.
6. In combination, an electromagnetically actuated controlling device, and a circuit including a liquid conductor connected in parallel with the circuit of the actuating winding of said controlling device, said liquid conductor being capable of and free to appreciably change the cross-sectional area of a portion thereof on the flow of current of a certain value therethrough for a time interval of appreciable and substantial duration.
7. In combination, an electromagnetically actuated controlling device, and means for causing operation of said device, said operating means comprising a liquid conductor connected in circuit with the actuating winding of said controlling means for producing a "pinch effect" on the flow of current of a certain value, the increase in the current in said actuating winding being greater than that in said liquid conductor on the occurrence of said "pinch effect", and the actuation of said controlling device being assisted by the proportionally greater increase in the current in said actuating winding than in the current in said liquid conductor.
- In testimony whereof I affix my signature, in the presence of two witnesses.

JAMES G. ZIMMERMAN.
